US00D604366S

(12) **United States Design Patent**
Liu et al.

(10) **Patent No.:** **US D604,366 S**
(45) **Date of Patent:** **** Nov. 17, 2009**

(54) **DISPENSING PACKAGE FOR RELEASEABLE
ADHESIVE TAGS**

(75) Inventors: **Jen-Rong Liu**, Kaohsiung Hsien (TW);
Chin-Chung Tsai, Taipei Hsien (TW);
Shu-Wei Ho, Kaohsiung Hsien (TW)

(73) Assignee: **Taiwan Hopax Chemicals Mfg. Co.,
Ltd.**, Kaohsiung County (TW)

(**) Term: **14 Years**

(21) Appl. No.: **29/302,346**

(22) Filed: **Jan. 15, 2008**

(51) **LOC (9) Cl.** **19-02**

(52) **U.S. Cl.** **D19/86**

(58) **Field of Classification Search** D6/515,
D6/518; D19/65, 67, 68, 69, 75, 78, 89,
D19/91, 92, 95, 99, 100; 206/215; 211/10,
211/11; 221/33, 35, 36, 47, 48, 49, 50, 51,
